UNITED STATES PATENT OFFICE.

EARL AMBERT MONTGOMERY, OF PASADENA, CALIFORNIA.

ARTICLE CARRIER.

Application filed July 21, 1924. Serial No. 727,297.

To all whom it may concern:

Be it known that I, EARL AMBERT MONTGOMERY, a citizen of the United States, residing at Pasadena, county of Los Angeles, 5 State of California, have invented new and useful Improvements in Article Carriers, of which the following is a specification.

My invention has reference, in its broad aspect, to improvements in article carriers 10 of the type adapted to be detachably supported upon a portion of a person's body whereby the object carried can be readily inspected at all times, will not interfere with free movements of the limbs, and will be 15 comparatively safe from damage; and more particularly it is my purpose to provide an article carrier of this type which is adapted to be mounted upon a person's forearm so that the article carried, as for instance a 20 watch, will be removed from objects grasped by the hands of the wearer, will not hamper the movement of the arm, and will be in full view at all times.

In certain occupations, as for instance 25 those of electric railway motorman, aviator, bus or coach driver, chauffeur, and the like, it is necessary to be constantly familiar with the time and by the same token complete control of the motor or vehicle must be 30 maintained which usually necessitates the employment of both of the hands of the operator. Heretofore wrist watches, watch hangers, fixed clock mountings, and other special devices have been employed to attain 35 the desired end but all fall short of accomplishment for the reason that carriers mounted on the wrist interfere with the movement of the wrist and hand or become covered by the coat sleeve or cuff, while fixed 40 mountings on the vehicle are subject to displacement and breakage and to undesirable vibration and jolts. Furthermore, these previous types of carriers are not disposed to avoid possible accidental knocks or blows 45 which result in the breaking of the instrument. My device on the other hand is subject to none of these disadvantages and may be mounted with facility irrespective of the type or thickness of the garment worn by 50 the operator.

While in the foregoing I have defined some of the advantages of my invention, other and equally important advantages are attributable to it among which are, briefly 55 stated; First, the employment of unique spring attaching members in lieu of the

usual strap fasteners; second, the utilization of a ribbed flexible casing for the spring members to prevent slipping of the carrier and wear upon a garment over which it is 60 attached, said casing being removable and replaceable; third, the provision of novel means for removably mounting the spring attaching members, and; fourth, the formation of the body of the carrier with unique 65 means for removably retaining a watch of the like and guarding it against accidental blows and knocks.

Furthermore, while I have here shown my article carrier as especially adapted to the 70 display of a watch, it is obviously capable and designed for the carrying of any instrument which is small and light enough to be supported upon the limb of a person. For instance, a compass, barometer, altitude 75 recorder, or any other instrument may be substituted in place of a watch, or it may be used as a carrier for a coin box and classifier or the like.

Consequently, while I have in the present 80 instance defined for the sake of illustration a specific form of my article carrier it will be understood that I do not desire to limit myself except as may be indicated by the scope of the claims appended hereunto and 85 forming a part of this specification.

In the drawing wherein is illustrated an embodiment of my invention;

Figure 1 is a front view of the carrier showing a watch retained in position there- 90 upon;

Figure 2 is an edge or side view of the carrier;

Figure 3 is a rear or bottom view of the carrier with one of the spring members re- 95 moved to show the manner of attaching the same to the body, and

Figure 4 is a detail view of one of the spring retaining members.

Like characters of reference refer to like 100 or similar parts throughout the several views of the drawing, in which;

The body (A) of my article carrier is formed with three layers or plies of material, preferably leather, designated respectively 105 (1), (2), and (3). The lowermost or base ply (1) is formed with two sets of slits (4) and (5) respectively. The slits of each set are parallel, and the corresponding slits of the two sets are relatively aligned so that 110 the terminals of the sets contemplate adjacent quadrangles. The base ply (1) is

stitched completely around its edges as at *a* to the intermediate ply (2), and said intermediate ply is preferably of the same shape as the base ply. Around each set of slits, 5 but slightly spaced therefrom, plies (1) and (2) are stitched together as at *b* so that the sets (4) and (5) resemble pockets open at both ends through the slits.

Superposed upon the intermediate ply (2) 10 is the top ply (3) which is formed with a central opening (6). The material of the ply is flared or pressed outwardly as at (7) to form a watch pocket (B), and it will be understood that by changing the shape 15 of the opening (6) and flared or pressed out portion that other articles of different sizes and shapes may be readily accommodated. Leading from the top edge of ply (3) and extending toward the opening (6) is a slot 20 (8); the material of the ply on either side of the slot being formed to provide ears (9) and (10). The ply (3) is stitched to the ply (2) around its bottom edge and partway up the sides as at *c*, and for further reinforcement of the respective plies 25 they are riveted together as at (11). Each of the ears (9) and (10) is provided with the female element of a snap fastener (12), the male element of which is carried by the intermediate ply. Thus, to arrange an article 30 in the pocket (B) the snap fasteners (12) are detached and the top ply bent back by grasping the ears (9) and (10); the point of bend being coincident with a line between rivets (11). The article, in the present instance a watch, having been disposed 35 in position, the top ply is fastened down thereupon with the projecting shank and stem arranged in the slot (8) between the ears as shown in Figure 1. A plush or other 40 similar soft pad (not shown) may be, and preferably is, affixed to the intermediate pad beneath the watch to more effectually support the same, and an opening α is provided 45 to hang the carrier upon a supporting hook.

Adapted to be inserted through the respective sets of slits (4) and (5) are a pair 50 of elliptical spring members (13), the free portions of which are adapted to engage about a person's forearm to hold the carrier in place. The ends of the spring members 55 are bent outwardly as at (14) to facilitate disposing the same upon the arm. Each spring member is sheathed in a ribbed or corrugated, flexible, tubular casing (15) to 60 prevent slipping and decrease wear upon a person's clothing. Each casing (15) is formed in two sections; a large section (16) adapted to cover the body of the spring, and a small section (17) adapted to cover the 65 end of the spring protruding from the slits forming the retaining pocket therefore. In mounting a spring member (13) upon the body (A), the small section (17) of

the casing is removed therefrom and the end 65 trained through the slits of one of the sets (4) or (5); the small section (17) is then replaced. It will thus be seen that the small sections of the casings also serve as retainers 70 for holding the springs in place, and obviously the casings are removable and replaceable in their entirety when they become worn or cracked.

While the operation of my invention and its advantages are believed to be apparent 75 from the foregoing, it is here pointed out that the spring attaching devices greatly facilitate the mounting and disengagement of the carrier in that they are simply snapped into place. Furthermore, they are 80 adaptable for disposition upon any sized forearm within limits, and can be worn over any type or character of garment.

Having described my invention and its objects with such attention to detail as will 85 thoroughly acquaint one skilled in the art with its construction and advantages, I claim—

1. An article carrier comprising a body 90 formed with slits therein, a substantially elliptical spring metal retaining member having spaced terminals adapted to be detachably mounted on the body and insertable through the slits with the spaced terminals directed laterally of the body, a two-part inherently resilient tubular protective covering for the retaining member and closely engaging the same to resist displacement or removal, the parts of said covering 95 being of unequal lengths, and an end of each of the respective parts of the protective covering being fitted close to the points of entry of the retaining member into the slits whereby to prevent dislodgment of the retaining member from the body or slipping 100 of the same from its normal position with respect thereto.

2. An article carrier comprising a body 105 formed with slits therein, a substantially elliptical spring metal retaining member having spaced terminals adapted to be detachably mounted on the body and insertable through the slits with the spaced terminals directed laterally of the body, a two-part protective tubular covering for the retaining member and closely engaging the same to resist displacement or removal, and an end of each of the respective parts of the protective casing being fitted close to the 110 points of entry of the retaining member into the slits whereby to prevent dislodgment of the retaining member from the body or slipping 115 of the same from its normal position with respect thereto.

In testimony whereof, I affix my signature hereunto.

EARL AMBERT MONTGOMERY,
